PAPER NAPKIN EMBOSsing, PRINTING, AND FOLDING MACHINE

John S. Burt, Highland Park, N. J., assignor to
 John Waldron Corporation, New Brunswick,
 N. J., a corporation of New Jersey

Application November 12, 1930, Serial No. 495,259

21 Claims. (Cl. 270—78)

This invention relates to a machine for embossing, printing, and folding paper napkins.

An important object of the invention is to provide a structure of this character in which 5 a plurality of napkins can be simultaneously produced and in which the produced napkins may, after embossing, be either passed directly to folding mechanism by which they are folded, cut, and stacked or passed to the printing mechanism through the printing mechanism forming a portion of the apparatus.

A further and more specific object of the invention is the provision in a structure of this character of a folding mechanism capable of 15 use in folding napkins of different sizes, and embodying a removable folding head by which the final folds are produced, removal or substitution of which is all that is necessary to permit the machine to be used with a different size of 20 napkin.

A further object of the invention is the provision of a rotary folding and cutting mechanism for producing final folds in the napkins and for severing the folded napkin from the 25 sheet from which it is produced.

A still further object of the invention is the production of means for controlling the position of both the napkin and the sheet while engaged with the folder.

These and other objects I attain by the construction shown in the accompanying drawings wherein, for the purpose of illustration, I have shown a preferred embodiment of my invention and wherein:

Fig. 1 is a side elevation of a napkin embossing, printing and folding machine constructed in accordance with my invention;

Fig. 2 is an outer end elevation partially in section of the folding mechanism;

Fig. 3 is a section on the line 3—3 of Fig. 2;

Fig. 4 is a section on the line 4—4 of Fig. 2;

Fig. 5 is a section on the line 5—5 of Fig. 2;

Fig. 6 is an enlarged section on line 6—6 of Fig. 3;

Fig. 7 is an end elevation of the folding cylinder and the associated mechanism;

Fig. 8 is a view similar to that of Fig. 6 with the folder rotated through 90 degrees;

Fig. 9 is a fragmentary horizontal sectional view through the folder; and

Fig. 10 is an end elevation of the folding mechanism illustrating the counting and stacking attachment.

Referring now to the drawings, and more particularly to Figure 1 thereof, the machine in-

cludes an embossing section 10, a printing section 11 and a folding section 12. In addition, in opposition to the embossing section, a stand 13 is provided for supporting a plurality of rolls 14 of crepe paper from which the napkins are formed. The embossing section includes a main embossing roll 15 and an associated pressure roll 16 and an auxiliary or name embossing roll 17 with its associated pressure roll 18 together with suitable rollers 19 for receiving one or more 10 of the webs W from the rolls 14 after their passage through the main embossing rolls and guiding them by, without passage through, a secondary or name embossing roll. This section further includes registering rolls 20, one for each 15 web W.

The printing mechanism 11 includes any suitable printing apparatuses 21, those at present illustrated being four in number, two for each web W so that multi-color printing may be resorted to. Each printing apparatus is shiftable in slides 22 so that its printing roll 23 may be moved into or out of engagement with an associated platen roll 24 from which the web may be directly fed to the folding mechanism 12. 20

The folding mechanism includes folding ploughs 25, one for each web, a pair of creasing rolls 26, carrier belt drive rollers 27, 28, a rotary folder and cutter 29 receiving the initially folded web from the creasing rolls to secondarily fold them, separate them from the web and deliver them to the carrier belts, a stacking mechanism 30 for receiving the napkins from the carrier belts and stacking them for removal from the machine and a counting mechanism 31 for 35 registering the number of napkins delivered to the stacking mechanism.

When the completed napkins are to be produced unembossed, or are to be primarily or secondarily embossed, the paths followed by the 40 webs W—W₁ are those indicated by solid lines in Fig. 1 of the drawings until the idler roller 19—a beyond the secondary embossing rolls is reached. From this point the web W₁ may follow either the dotted line course "A", or the solid 45 line course which is indicated, the web W following its solid line course. It will be obvious that by placing pressure on the primary embossing roll 15, with the napkins following either of the alternate paths just indicated, a primary 50 embossing of both webs will be effected and it will likewise be obvious that after such primary embossing a secondary embossing may take place, where this is desired, by placing pressure on the secondary embossing roll 17 through its roll 55

18. If it is desired that both webs be primarily embossed but only one thereof secondarily embossed, as for example when producing at the same time napkins for two different customers, 5 only one of whom wishes the secondary or name embossing feature, then the web W-1 may follow the dotted line course B about rollers 19 and from this roller to the registering roller 20 may follow either branch B-1 or B-2 of this course 10 dependent upon whether it is to follow the solid line course of the web W-1 of the dotted line course A thereof. Thus, the napkins produced from the webs may be either unembossed and unprinted or printed, primarily embossed and printed, or unprinted, primarily and secondarily embossed and printed or unprinted, or the webs 15 may be divided after the primary embossing operation and one of these webs secondarily embossed and printed or not as desired while the 20 second web is delivered with only the primary embossing or with primary embossing and printing as desired.

The machine is thus very flexible in production and will satisfy every need in the production 25 of paper napkins.

It will, of course, be understood that where printing is resorted to this printing may be done by one or more of the printing groups associated with each web so that the printing is in one or 30 more colors as desired.

Of the folding mechanism 12 the ploughs 25 are of usual construction comprising a wedge-shaped plate over which the web W is led from the butt toward the point end, and the point end 35 of which is directed between the creasing rollers 26. The rotary folding and cutting mechanism 29 receives the longitudinally folded web to form a transverse fold therein at the center of what is to be a completed napkin and then severs the 40 napkin end and delivers it between delivery belts 32 and 33 which operate face to face and, as hereinbefore stated, deliver the napkin to the folding mechanism 30.

This rotary folding and cutting mechanism 45 comprises a base 34 having flanges 35 along its side edges operating in slides 36 having means 37 associated therewith to clamp the base in adjusted position. Arising from the base are bearings 38 in which a shaft 39 is journaled. Secured to the shaft 39 between the bearings 38 50 is a drum 40 constructed to provide circumferentially-spaced, longitudinally-extending pockets. These pockets, as more clearly shown in Fig. 8, are formed in diametrically-arranged 55 pairs indicated by numerals 41 and 42 respectively. In the pockets 41 are arranged pairs of jaws 43, each jaw comprising a plate 44 (Fig. 9) extending longitudinally of the pocket and having its inner face at the outer edge thereof milled 60 or otherwise roughened as at 45 to produce a gripping surface.

Each plate has formed therein a series of longitudinally-spaced openings 46 with which communicate the inner ends of slots 47, the outer ends of which open through the inner edges of the plates. Springs, in the form of split rings, 48, 65 retain the jaws with their gripping faces 45 normally in engagement, each spring being composed of material of a thickness such that it may 70 be entered in the openings 46 through the slots 47 and then rotated so that its end portions may engage in notches 49 formed in the plate. The inner end edges of the plates are arranged in longitudinally-extending grooves 50 formed in 75 the inner wall of the pocket 41. Longitudinally-

extending bars 51 mounted in the side walls of the pockets 41 and notched at 52 to receive the springs 48 serve to retain the jaws in position in the pocket, each bar 51 mounting a tube 53 having small outlet openings for a purpose presently to appear.

Between each pair of jaws is arranged a camming shaft 54, the ends of which project through the end walls 55 of the drum and have secured thereto arms 56 the inner ends of which 10 have rollers 57 engaging stationary cams 58. Cams 58 are each provided with a peak 59 serving to elevate the rollers radially outward thereby rotating the shaft and moving the jaws through the action of the cams from the position shown in the lower portion of Fig. 8 to the 15 position shown in the upper portion thereof.

As will be noted from an inspection of the cam shown in this figure in dotted lines, the cam serves to maintain the jaws in open position from a point 20 where the napkin N is disengaged from the jaws to a point opposed to a tucker blade 60. This tucker blade is mounted upon a shaft 61 mounted at its ends in bearings supported from the bearings 18 and driven from the drum in timed relation thereto, as for example, by 2 to 1 reduction gearing indicated generally at 62. Just prior to the closing of the jaws occurring through springs 48 upon release of the rollers 57 from the peaks 59 of the cams 58, this tucker blade enters between the jaws moving before it the web "W" 25 so that as the jaws close, they close upon the web and form a transverse fold in the web. The tucker blade is at present shown as formed in two sections but may, obviously, if so desired, be 30 formed in a single section.

In the pockets 42 are disposed knives 63 and retaining wedges 64 therefor. Each knife 63, at each rotation of the drum, is brought into co-operative relation to a stationary knife blade 65 carried by the base 34 and mounted for adjustment toward and away from the drum so that proper co-action with the movable knife blades may be had.

The outer or rear end of the shaft 39 has 45 mounted thereon a relatively stationary distributor head 66 held in position against the end of the shaft by a spring-pressed thrust bearing 67. This distributor head has two inlets designated at 68 and 69 respectively, each inlet communicating with a longitudinally-extending port 70 opening through the inner face of the head. Shaft 39 has formed therein 4 longitudinally-extending ports 71, each communicating through a radial port 72 formed partially in an adjacent 50 end head 73 of the drum and partially in the shaft with one of the tubes 53. The inlets 68 and 69 are in communication through valved branch pipes 74 with a source of pressure generally designated at 75, these branch pipes preferably having arranged therein couplings 76 permitting their 55 ready disconnection from the source for a purpose presently to appear.

The valves 77 of the branch pipes 74 are of the spring-seated type and have associated therewith operating members 78 each in the form of a lever, one end of which is connected through a spring 79 with the base 34 and the other end of which overlies the stem 80 of the valve. Each lever has a roller 81 to operate against the periphery of a cam 82 or 83. These cams are carried by the end of the tucker blade shaft 61 and are, accordingly, rotated twice for each rotation of the drum. When the valve 77 of the branch 74 communicating with inlet 69 is actuated, which occurs as one 70 75

of the jaw assemblies is co-operating with the tucker blade, and the cutting operation is taking place between a movable knife 63 and the stationary knife 65, a blast of air is delivered through 5 a tube 53 and the ports thereof, this tube lying immediately in advance of and adjacent to the jaw assembly which is co-acting with the tucker blades. This results in the severed end of the napkin web being blown outwardly from the 10 surface of the drum as indicated in Fig. 6 of the drawings so that this end of the napkin may finally assume a position where it trails from the jaws and overlies what is to be the other end of the folded napkin.

15 When the valve of the other branch is actuated, which occurs when the drum has been rotated through approximately 90 degrees from the position just mentioned, a blast of air is delivered to the tube 50 trailing a jaw assembly which is arranged in proximity to the delivery belts 32. This blast of air is delivered at the time when the jaw assembly opens to permit escape of the napkin, and the napkin is, accordingly, blown against an overlying delivery belt and held thereagainst 20 by the blast until it comes into the bight 84 between these belts.

25 It will be noted that the peak of cam 83 controlling the latter operation is relatively long while that of cam 82 controlling the former operation is relatively short, this difference in sizes being due to the fact that in the first instance it is merely necessary to blow the napkin away from the surface of the roll the speed of the roll then acting to retain the blown out end in a 30 trailing position while in the latter operation it is necessary that the blast be continued until the napkin actually enters the bight between the belts 32. The drive for the rotating folder and cutter is at present shown as derived from a gear 85 on 35 the shaft of the belt drive roller 28.

40 Any suitable means for driving the drum may be provided, but any means provided should be of such character that it will not interfere with removal of the drum and its base from the folder 45 section 12 as a unit. It will be noted that by freeing the base 34 and disconnecting the branch conduits 74 at the coupling 76 thereof, the unit represented by the valve mechanism, the rotary folder 29 and the associated tucker blade, may be bodily 50 removed for substitution by a further unit wherein the diameter of the rotary folder 29 is of greater or smaller size, thus permitting use of the apparatus in producing napkins of different sizes with but a slight change in the machine structure. It will, of course, be understood that the 55 ploughs 25 will fold webs of any width which may be desired.

55 In order that the controlling blasts of air employed in conjunction with the operation of the rotary folder may act properly upon the napkins when delivered thereto, the periphery of the drum is preferably grooved as indicated at 86 so that the air blast may move circumferentially of the drum and the tendency of the napkins to cling to the surface of the drum may be reduced.

60 The delivery belts 32 are in the form of straps, these straps being arranged in pairs and the straps of the pairs being aligned with one another. During delivery travel of these belts the faces thereof are in opposition, coming into engagement with one another at the bight 84 and continuing between rollers 27 and 28 over a further roller 87 arranged above and inwardly of the open inner end of the stacking rack 88 and

then downwardly past the inner face of the rack. Below the rack the inner belt is returned over idlers 89 and 90 to the roll 28 while the outer belt returns over idlers 91 and 92, roller 27 and idler 93 to the periphery of roller 28.

5 Means for removing the napkins from between the delivery belts to the rack 88 comprises a stop member 94 limiting the downward travel of the napkins in their vertical delivery travel so that they are properly aligned for entry in the rack 10 and an oscillatory member including fingers 95 to pass between the stops forming the delivery belts and deliver the napkin into the rack. Stop 15 94 is at present shown as in the form of a lever including the stop proper, a shaft 96 and a relatively short arm 97. The short arm 97 projects adjacent one face of a ratchet disk 98 having arranged thereon one or more pins 99 adapted to engage the arm and by engaging the same to elevate stop 94 so that the napkin is held in an 20 elevated position and will project above the remaining napkins of the rack when delivered thereto as indicated at N' in Fig. 2. Travel of the ratchet disc is accomplished through a pitman connection 100 with the inner end of shaft 25 61 to a bell crank mechanism 101 including a dog 102 for co-action with the teeth of the disc. Operation of the oscillatory member for removing the napkins to the rack from between the delivery belts is accomplished through a pitman 30 connection 103 between the inner end of drive roll 28 and a crank arm 104 mounted on a shaft 105 to which the oscillatory mechanism is secured. Shaft 105 preferably provides a mounting for the ratchet disc 98 and the bell crank 35 mechanism 101.

35 In the production of napkins with a machine of this character, assuming that it is desired that the produced napkins be plain, with the exception of a general embossed pattern; the webs 40 are passed about the primary embossing roll and then directly over the platens 24 to ploughs 25 where they are given the longitudinal fold. This fold is creased between rolls 26 and the webs are then delivered to the rotary folder and cutter 29. 45 The tucker blade 60 engages each web in a pair of the jaws 43 and the fold formed by this blade is retained between the jaws due to the fact that the gripping portions of the jaws are roughened while the tucking end of the blade 60 is tapered 50 and smoothed. Simultaneously with the gripping of the newly formed tuck, the preceding portion of the napkin is severed by co-action of a knife 63 with the stationary knife blade 65 and a blast of air is delivered beneath the portion of 55 the napkin lying between the gripping jaws and the active cutting blade so that the free end of the napkin is blown outwardly from the roll and may assume a trailing position. This trailing position is assured as the jaws pass the stationary knife 65 which acts to engage against the freed end of the web should it project. After 60 passing knife 65 and after rotation of the drum from the point where the gripping action took place through 180 degrees, the napkin gripped by the jaws is freed from the web by action of the following cutting knife of the drum against stationary knife 65. After passing through a further 90 degrees or through a total of 270 degrees from the gripping point, the jaws gripping the napkin are opened and at the same time a 70 blast of air is delivered through the tube 53 immediately following the jaws. This blast of air which is continued through a relatively long 75

period of rotation of the drum forces the napkin against the inner delivery belt and maintains it against this inner delivery belt until it is engaged by both belts at sight 34. The napkin then moves between the delivery belts until it reaches the stacking mechanism into which it is delivered, as previously described.

The cycle for production of napkins which are both primarily and secondarily embossed differs from the foregoing only in that the webs after passage over the primary embossing rolls are passed over the secondary embossing roll before delivery to the ploughs 26. It will, of course, be understood that one of the webs can be passed to the secondary embossing roll alone and the other passed directly to its plough, or both webs can be passed over these rolls. Similarly, either of the webs in either of the arrangements above described may be passed through the printing mechanism before delivery to the ploughs.

Since the construction hereinbefore set forth is obviously capable of a considerable range of change and modification without in any manner departing from the spirit of my invention, I do not wish to be understood as limiting myself thereto except as hereinafter claimed.

I claim:

1. In a folder, a rotating roll having pairs of circumferentially-spaced, longitudinally-extending gripping jaws normally in gripping relation to one another, a tucking blade associated with the roll and operating in timed relation thereto for tucking a web between the jaws to be held thereby during rotation of the roll, a longitudinally-extending cutting blade arranged between adjacent pairs of jaws and a stationary cutter blade associated with the roll for co-action with said cutter blade to sever the trailing portion of the web from that gripped in the jaws.
2. In a folder, a rotating roll having pairs of circumferentially-spaced, longitudinally-extending gripping jaws normally in gripping relation to one another, a tucking blade associated with the roll and operating in timed relation thereto for tucking a web between the jaws to be held thereby during rotation of the roll, a longitudinally-extending cutting blade arranged between adjacent pairs of jaws, a stationary cutter blade associated with the roll for co-action with said cutter blade to sever the trailing portion of the web from that portion gripped in the jaws, and means for forcing the trailing portion of the web outwardly from the roll as it is severed by said blades.
3. In a folder, a rotating roll having pairs of circumferentially-spaced, longitudinally-extending gripping jaws normally in gripping relation to one another, a tucking blade associated with the roll and operating in timed relation thereto for tucking a web between the jaws to be held thereby during rotation of the roll and at a point spaced from the end of the web, and means to sever the trailing portion of the web from that gripped in the jaws at a point in alignment with the end of the web, including a shear blade carried by the roll and a stationary shear blade co-acting with the shear blade of the roll.
4. In a folder, a rotating roll having pairs of circumferentially-spaced, longitudinally-extending gripping jaws normally in gripping relation to one another, a tucking blade associated with the roll and operating in timed relation thereto for tucking a web between the jaws to be held thereby during rotation of the roll, means to sever the trailing portion of the web from that

gripped in the jaws, and means carried by the roll for forcing the trailing portion of the web outwardly from the roll as it is severed by the last-named means.

5. In a rotary folder, a rotating roll having a pair of longitudinally-extending gripping jaws normally resiliently held in gripping relation to one another, means associated with the jaws for opening the same through a portion of the rotation of the drum and a tucking blade associated with the roll and operating in timed relation thereto for tucking the web between the jaws to be held thereby during rotation of the roll until the jaws are reopened and air blast means for blowing the web outwardly from the roll as the jaws are opened.

6. In a rotary folder, a rotating drum having a pair of longitudinally-extending gripping jaws normally resiliently held in gripping relation to one another, means associated with the jaws for opening the same through a portion of the rotation of the drum, a tucking blade associated with the roll and operating in timed relation thereto for tucking the web between the jaws to be held thereby during rotation of the roll until the jaws are reopened, and means including a part carried by the drum and a part stationary with relation to the drum for severing the trailing portion of the web from that gripped in the jaws.

7. In a rotary folder, a rotating drum having a pair of longitudinally-extending gripping jaws normally resiliently held in gripping relation to one another, means associated with the jaws for opening the same through a portion of the rotation of the drum, a tucking blade associated with the roll and operating in timed relation thereto for tucking the web between the jaws to be held thereby during rotation of the roll until the jaws are reopened, means including a part carried by the drum for severing the trailing portion of the web from that gripped in the jaws, and means carried by the drum for forcing the trailing portion of the web outwardly from the drum as it is severed by the last-named means.

8. A machine for producing folded articles from a web, means for feeding the web, a folder unit engaging the web to fold the same and to sever the article from the web and a driving connection between said folder unit and said web feeding means, said unit being bodily removable.

9. In a machine for producing folded articles from a web, means for feeding the web, a folder unit comprising a rotating drum driven from said web feeding means and supporting means for said drum including a part co-acting with a part carried by the drum to sever the formed article from the web, said drum and its supporting means being bodily removable by a movement axial to the drum.

10. In a machine of the class described, a rotating head having circumferentially-spaced pairs of normally closed gripping jaws, means for opening the jaws during a portion of each rotation of the head, means for tucking a web between the jaws as they are closing and means for severing the web between the pairs of jaws including a shear blade carried by the head and a stationary shear blade co-acting with the shear blade of the head.

11. In a machine of the class described, a rotating head having circumferentially-spaced pairs of normally closed gripping jaws, means for opening the jaws during a portion of each rotation of the head, means for tucking a web between the jaws as they are closing, means for

severing the web between the pairs of jaws, and pneumatic means for forcing the end of the web in advance of the pair of jaws last engaged therewith outwardly from the head.

5. 12. In a machine of the class described, a rotating head having normally closed gripping jaws, means for opening the jaws during a portion of each rotation of the head, perforated pipes carried by the head and paralleling the jaws

10 on opposite sides thereof, and a distributor for alternately delivering fluid pressure to said pipes.

13. In a machine of the class described, a rotating head having normally closed gripping jaws, means for opening the jaws during a portion of each rotation of the head, perforated pipes carried by the head and paralleling the jaws on opposite sides thereof, and a distributor associated with said head and delivering air to the pipe in advance of the jaws as the jaws are closing and to the pipe rearwardly of the jaws as the jaws are opening.

14. In a machine of the class described, a rotating head having normally closed gripping jaws, means for opening the jaws during a portion of each rotation of the head, perforated pipes carried by the head and paralleling the jaws on opposite sides thereof, a distributor associated with said head and delivering air to the pipe in advance of the jaws as the jaws are closing and to the pipe rearwardly of the jaws as the jaws are opening, and a delivery mechanism associated with said head and including belts traveling face to face through a portion of their length, one of said belts including a portion opposing the head at the moment of opening of the jaws.

15. In a machine for primarily and secondarily folding and stacking a web, primary folding mechanism, stacking mechanism and an intermediate disposed folder embodying a rotating drum having folding jaws, a tucking mechanism for the web engaging the web between said jaws and means for severing the web from the portion thereof engaged in the jaws after a predetermined rotation of the drum from the tucking position, said drum, tucking and cutting mechanism being removable as a unit.

16. In a machine of the class described, a rotating drum having normally closed gripping jaws, a tucker associated with and operating in timed relation to said drum for tucking a web between the jaws, pneumatic means for controlling the position of the web with relation to the jaws and means associated with and operated by said tucking means controlling the operation of said pneumatic means.

17. In a machine of the class described, a rotating head having circumferentially-spaced pairs of gripping jaws, means for consecutively tucking a web between the jaws of each pair as the head is rotated, means for severing the web between the jaws, and means for delivering a blast of air through the head for blowing the portion of the web in advance of the jaws last engaged therewith outwardly from the head.

18. In a folder, a rotating drum and an associated tucker rotating about an axis stationary with relation to the drum, means for feeding a plurality of webs in side to side relation between the tucker and the drum, a plurality of circumferentially spaced means carried by the drum 15 for engaging a tuck formed by the tucker, a shear carried by the drum between said tuck-engaging means and a stationary shear to act upon the webs when stretched between said tuck-engaging means in co-action with the shear of the drum. 20

19. In a folder, a rotating drum and an associated tucker rotating about an axis stationary with relation to the drum, means for feeding a plurality of webs in side to side relation between the tucker and the drum, a plurality of circumferentially spaced means carried by the drum 25 for engaging a tuck formed by the tucker, a shear carried by the drum between said tuck-engaging means, a stationary shear to act upon the webs when stretched between said tuck-engaging means in co-action with the shear of the drum, and means carried by the drum adjacent each tucking means for directing the end of the severed web in advance of the tucking means outwardly from the drum as it is severed. 30

20. In a folder, a rotating drum and an associated tucker comprising a blade continuously rotating about a fixed axis to which the blade is radial, said axis being stationary, means for feeding a web between the drum and tucker, 40 means carried by the drum for gripping a tuck formed by the tucker and means including a part carried by the drum for severing the trailing portion of the web from that portion thereof 45 gripped by said gripping means.

21. In a machine of the class described, a rotating head having normally closed gripping jaws, means for opening the jaws during a portion of each rotation of the head, means for tucking a 50 web between the jaws as they are closing, and air blast means carried by the head for forcing the web outwardly from the head as the jaws are opened.

JOHN S. BURT. 55
